DESIGN FOR A CURTAIN DISPLAY RACK

Albert Bersin, Brooklyn, and Louis Samuels,
New York, N. Y.

Application May 21, 1941, Serial No. 101,059

Term of patent 7 years

To all whom it may concern:

Be it known that we, Albert Bersin, a citizen of the United States, residing in Brooklyn, in the county of Kings and State of New York, and Louis Samuels, a citizen of the United States, residing in New York, in the county of New York and State of New York, have invented a new, original, and ornamental Design for a Curtain Display Rack, of which the following is a specification, reference being had to the accompanying drawing, forming part thereof.

Figure 1 is a perspective view of a curtain display rack, showing our new design.

Figure 2 is a top plan view of the rack showing 16 frames in place.

Figure 3 is an end elevational view of the rack.

We claim:

The ornamental design for a curtain display rack, as shown.

ALBERT BERSIN.
LOUIS SAMUELS.
